HEN'S NEST

Clarence G. Muehlfeld, Bridgeport, Mich.

Application October 29, 1948, Serial No. 149,380

Term of patent 14 years

(Cl. D12—2)

To all whom it may concern:

Be it known that I, Clarence G. Muehlfeld, a citizen of the United States of America, residing at Bridgeport, in the county of Saginaw and State of Michigan, have invented a new, original, and ornamental Design for a Hen's Nest, of which the following is a specification, reference being had to the accompanying drawing, forming part thereof.

In the drawing:

Fig. 1 is a perspective view of a hen's nest, showing my new design.

Fig. 2 is also a perspective view, taken from the end opposite to that shown in Fig. 1, with the egg compartment cover shown in open position.

Fig. 3 is a view similar to Fig. 1 and showing the nest door and the egg compartment cover in open position.

I claim:

The ornamental design for a hen's nest, as shown.

CLARENCE G. MUEHLFELD.
